UNITED STATES PATENT OFFICE.

CLARENCE D. PLATT, OF BRIDGEPORT, CONNECTICUT.

ENTRANCE-SWITCH UNIT.

1,306,191.

Specification of Letters Patent. Patented June 10, 1919.

Application filed March 9, 1918. Serial No. 221,362.

To all whom it may concern:

Be it known that I, CLARENCE D. PLATT, a citizen of the United States of America, residing at Bridgeport, Connecticut, have 5 invented a new and useful Entrance-Switch Unit, of which the following is a specification.

My present invention relates to electric meters.

10 An important object of the invention is to combine the meter and the appurtenances with which it is usually associated, such as the fuses and entrance switch, into a single unit of convenient size and form for handling, and which may be treated as a unit in the handling and installation of the meter and its appurtenances.

Another object is to provide a meter unit of this character in which all parts will be 20 thoroughly protected and will be guarded against tampering by unauthorized persons.

Other objects are to construct the meter unit in such form that the meter can be easily read at any time and so that the fuses 25 may be readily renewed by one authorized to do this. In this connection it is one of the aims of the invention to segregate the "line" and "load" fuses and to make the load fuses accessible to the customer and 30 the line fuses accessible only to an authorized agent of the power company, or the like.

The invention also has for its aims to provide practical and efficient locking means 35 for the various elements of the device, to provide for the locking of the switch either in "on" or "off" position and to provide a desirable form of indicator for showing the condition of the switch.

40 Another object is to make the device "safe" for renewal of the fuses by insuring that the switch be turned to the "off" position before the fuses can be replaced.

A further object is to construct the device 45 so that it may be readily connected with the respective line and load circuits.

Briefly stated, the invention comprises in 50 a preferred form, a box constituting the shell or casing of the device and forming a housing containing the meter and entrance switch, together with the fuses and electrical connections appurtenant to these parts. The meter and its associated parts being thus entirely housed are protected and may 55 all be placed in service by simply mounting the unit where desired and connecting the line and load wires at the proper terminals

provided therefor. The box in this preferred form is provided with a cover having a window exposing the dial of the meter and 60 within this cover there is another cover over the switch and the electrical connections within the box, this inside cover being constructed to expose the fuse sockets when the outer cover is open. In connection with 65 these fuse sockets, there is provided a guard which is arranged to be actuated by the switch, said guard normally protecting the fuse sockets and being shifted to uncover said sockets only when the switch is thrown 70 to the "off" position. This movable guard may be utilized as an indicator for showing the condition of the switch.

The various other features of the invention, such as the special locking means and 75 the construction for facilitating wiring of the device will all appear as the specification proceeds, attention being now directed to the accompanying drawings, wherein I have illustrated the invention embodied in a 80 practical commercial form.

In said drawings:—

Figure 1, is a front or face view of the device as it appears normally in the closed and locked position.

85 Fig. 2, is a similar view with the outer cover unlocked to permit renewal of the load fuses.

Fig. 3, illustrates the inner cover lifted to give access to the switch, the line fuses 90 and the various wiring connections.

Fig. 4, is a side view of the device with the inner and outer covers shown in dotted lines as partly opened.

Fig. 5, is a longitudinal sectional view 95 taken substantially on the plane of the line 5-5 of Fig. 1.

Fig. 6, is a detached perspective view of the combined guard and indicator slide.

Referring to the drawings now in detail, 100 7 designates the body portion of the box or casing, constructed usually of sheet metal and of a size to accommodate the meter and its appurtenances.

The meter is designated 8, the same being 105 of any conventional or suitable type. This meter is shown as provided with dials 9 and with a "wiring chamber" 10, as usual in such structures. The meter is shown mounted in the upper end of the box, which is of more or less elongated construction and may be secured in place therein by suitable fastenings.

110 In the construction illustrated, the switch

and the fuses are all mounted on a single insulating base 11 secured in the lower portion of the box below the meter. This base carries a set of terminals 12 at its lower end 5 to receive the line wires 13 and along side these a set of terminals 14 to receive the load wires 15.

The switch is shown as a pair of switch blades 16 coupled up by a cross bar 17 and 10 arranged to engage at their free ends the contact clips 18, said switch blades being pivoted at their lower ends at 19 on the hinge posts 20 which are connected with the line terminals 12.

15 21 designates the fuse sockets for the line fuses, these sockets being shown mounted on the insulating base 11 above the switch and connected with the contact clips 18 by suitable back-connections 22. Terminals 23 are 20 shown provided at the upper edge of the insulating base connected with the line fuse sockets, said terminals being connected as by means of wires or suitable strap connections 24 with the in-going terminals 25 on the wiring 25 chamber of the meter.

26 designates the load fuse sockets which are shown mounted at the upper edge of the insulating supporting base at one side of the line fuse sockets and provided with the terminals 27 connected by suitable strap or wiring connections 28 with the out-going terminals 29 of the wiring chamber. These load fuse sockets are connected as by means of suitable back-connections 30 with the load 35 terminals 14. The load fuse sockets are, as appears in Figs. 3 and 5, located on a higher plane than the line fuse sockets, the insulating base for this purpose being provided with a raised table portion 31.

40 The inner cover for the switch, line fuses and electrical connections is designated 32 and is shown pivoted at 33 between the side walls of the box. This pivotal mounting is shown as off-set from the body of the cover 45 as indicated in Fig. 5 to cause the cover as it swings open (Fig. 4) to swing clear of and fully disclose the various terminals and wiring connections between the meter and the combined switch and fuse block as shown in 50 Fig. 3. The lower portion of this inside cover is off-set or raised above the plane of the upper hinge end of the cover as indicated at 34 to provide room for the opening movement of the movable switch element (Fig. 5) and is cut out at 35 over the raised table portion 31 of the fuse block so as to leave the load fuses uncovered when said cover 55 is in closed position, (Fig. 2).

The outer cover is designated 36 and is 60 shown pivoted at 37 at the upper end of the box. This outer cover is provided with a window 38 therein for exposing the dial of the meter. This window may simply be an opening formed in the cover of a size to expose the dial of the meter.

From what has been said it will be seen that with the parts in the normal condition as indicated in Fig. 1, the meter, with its appurtenances such as the entrance switch, fuses and various wiring connections, will be entirely protected but the meter can be read without disturbing any of the parts and further that when the outer cover is opened, as indicated in Fig. 2, the switch, electrical connections and line fuses will be covered 75 but the load fuse sockets will be exposed. Thus, when the outer cover is opened, the load fuse sockets will be made accessible for the renewal of fuses but the line fuses, switch and all other parts will be kept covered and 80 protected. Therefore by placing the control of the outer cover in the hands of the customer or user of the current and keeping the control of the inner cover in the hands of an agent of the power company, the customer is enabled to renew the load fuses when necessary, but is unable to change the line fuses or any of the wiring connections, etc. As a further precaution against substitution of fuses, the line fuse sockets might 85 be of a different character from those of the customer's fuse sockets.

90 As a means of protecting the customer when renewing the load fuses, means are 95 preferably provided for insuring that the switch will first be thrown to "off" position before the fuses can be replaced. Accordingly I have shown a guard in the form of a slide 39 which in the circuit closed position (Fig. 5) overlies or covers the load fuses 40 100 in the load fuse sockets 26 and is connected with the switch so as to uncover said fuses when the switch is shifted to the open circuit position. This guard slide as indicated in Fig. 6, may be in the form of a plate slidably 105 confined to the under side of the inner cover as by means of rivets or studs 41 received in slots 42 in said plate. This plate may be reinforced at its edges as by means of dependent flanges 43. One of said flanges is 110 here utilized as a part of the connections between the plate and the switch, it having for the purpose a slot 44 therein receiving the cranked portion 45 of the switch operating shaft 46. This switch operating shaft is shown journaled at 47 in the opposite side walls of the box and as having an external 115 operating handle 48. The cranked portion of said shaft is shown connected with the removable switch element by a suitable strap connection 49 engaged with the cross bar 17.

120 The operation of this guard slide will be clear from Fig. 5 wherein, it will be seen that when the switch is closed, the slide will be- 125 cause of the connections described cover the top of the load fuses and will, as the switch is thrown open, be shifted downward to uncover the load fuses. The customer therefore must open the switch before the load fuses can be removed or inserted.

The guard slide is further utilized in the present disclosure as a switch indicator, it bearing on the face thereof indications 50 such as the words "On" and "Off" visible 5 through registering openings 51 provided in the inner and outer covers. This shows at a glance the condition of the switch either when both covers are closed (Fig. 1) or when the outer cover alone is open (Fig. 2).
 10 The guard slide may be furthermore utilized as a means for locking the switch in a predetermined condition. Thus with the inner cover thrown open and the slide disengaged from the switch, the switch may be 15 closed and the slide be shifted to its extreme lower position, whereupon the upper end 52 of the dependent slotted flange will stand in back of the rocker arm portion 45 of the switch operating shaft and so lock said 20 switch in its closed position. If then the covers are locked the switch will be positively locked against further operation.

The electrical connections between the fuse block and the meter will preferably be 25 made at the factory at the time of mounting the parts in the box so as to leave nothing to be done by the contractor but to secure the unit in place upon the wall or other support and connect the line and lead 30 wires with the proper terminals. To facilitate the connection of the line and lead wires with these terminals I have shown the lower end wall of the box as cut down to reduce its height as indicated at 53 so as to give 35 easy access to the terminals when introducing these wires into the box. To cover this cut-away portion in the lower end of the box I have shown the inner cover as provided with a dependent angular flange or 40 extension 54 and this flange may be utilized further as a means for the securing of the inner cover in closed position, as by providing it with a perforated ear 55 for registry with a similar ear 56 on the bottom wall of 45 the box, with which may be engaged the hasp of a padlock 57 or other suitable securing or sealing means.

Locking or sealing means are also preferably provided for the outer cover, such 50 means being here illustrated as a padlock 58 having its hasp passed through registering openings 59 and 60 in the top and angular flange portions respectively of the outer and inner covers.

55 My invention also contemplates the locking of the guard slide by means of this same padlock, the hasp of said padlock being shown as passing also through one of the slots 42 in said locking slide when said slide 60 has been retracted into the position indicated by dotted lines in Fig. 5. This enables the switch being locked in "off" position by first removing the padlock and then throwing the switch to open circuit position and 65 engaging the hasp of the padlock with the

registering openings in the two covers and the locking slide.

In practice the outer cover may simply be latched in closed position, or if a lock is used, the customer may be provided with a 70 key so that he may open the same for renewal of the load fuses. The inner cover may be sealed by the power company, or if a lock is provided, it may be such as can only be opened by an agent of the power 75 company.

The invention will thus be seen to provide proper protection for both the consumer and the power company and all parts of the device are properly housed and protected 80 from dust, etc. Another valuable point of the invention is that the consumer is prevented from drawing power in excess of that to which he is entitled, the line fuses under control of the company determining 85 the load which can be withdrawn even though the consumer takes advantage of his access to the load fuses to insert fuses at this point having a carrying capacity in excess of the current to which he is entitled. 90

I claim:—

1. A meter unit comprising a box, a meter and a fuse base having line and load fuses mounted in said box, a cover for said box arranged when closed to expose only the 95 dial of the meter, and when open to expose substantially the entire interior of the box, a movable guard within the box exposed when the cover is open and adapted to cover the fuse base when said cover is open, means 100 for shifting said guard to uncover the load fuses only and further means independent of the cover aforesaid adapted to be operated to uncover the entire fuse base including the line fuses. 105

2. A meter unit comprising a box, a meter within the box, a fuse base having line and load fuses and a switch within the box connected with the meter and the fuses, a cover for the box arranged when closed to 110 disclose only the dial of the meter and to expose substantially the entire interior of the box when open, a load fuse guard within the box for covering the load fuses when the switch is closed and the cover is open, 115 means for operating the switch, and connections between said switch operating means and guard for operating the latter to uncover the load fuses when the switch is actuated, whereby both the line and load fuses 120 will be covered when the switch is closed and the cover is open and whereby the load fuses only will be uncovered when the switch is opened and the cover is open.

3. A meter unit comprising a box, a meter within the box, a switch and a fuse base having line and load fuses within the box electrically connected with the meter, a cover for the box arranged to disclose only the dial of the meter, and a second cover 130

- within the box for covering the switch and electrical connections and arranged to leave the load fuses exposed when the outer cover is open.
5. 4. A meter unit comprising a box, a meter within the box, a switch and fuse base within the box electrically connected with the meter, a cover for the box arranged to disclose only the dial of the meter, a second cover within the box for covering the switch and electrical connections, a movable guard for covering the fuse base when the outside cover is open, and switch operating means connected with said guard for shifting the same to uncover a portion of the fuse base when the switch is operated. 70
10. 4. A meter unit comprising a box, a meter having a wiring chamber housed in said box, a switch in the box, line fuse sockets and load fuse sockets within the box, electrical connections between said switch, meter and fuse sockets, a movable cover over said switch, line fuse sockets and wiring connections arranged to expose the load fuse sockets, an outer cover housing the inner cover and the load fuse sockets, a movable guard over the load fuse sockets, and means for shifting said movable guard to uncover the load fuse sockets when the outer cover is open. 75
15. 5. A meter unit comprising a box, a switch mounted in said box, line and load fuse sockets mounted in the box, a meter having a terminal chamber housed in said box, electrical connections between the switch, meter and fuse sockets, a cover for the switch and wiring connections aforesaid, a movable guard for the fuse sockets, switch operating means connected with said guard for shifting the same to uncover the load fuse sockets when the switch is operated, and an outside cover for the box arranged to cover the movable guard and inside cover. 80
20. 6. A meter unit comprising a box, a switch mounted in said box, line and load fuse sockets mounted in the box, a meter within the box, electrical connections between the switch, meter and fuse sockets, a cover for the switch and wiring connections aforesaid, a movable guard for the load fuse sockets, switch operating means connected with said guard for shifting the same to uncover the load fuse sockets when the switch is operated, and an outside cover for the box arranged to cover the movable guard and inside cover. 85
25. 7. A meter unit comprising a box, a meter within the box, a switch mounted in the box, line and load fuse sockets within the box, electrical connections between the switch, meter and fuse sockets, a cover for the box having a window exposing the dial of the meter, a second cover within said outside cover and arranged to cover the wiring connections and switch, and a movable guard for the load fuse sockets connected to operate in unison with the switch. 90
30. 8. A meter unit comprising a box having a movable cover provided with a window therein, a meter mounted wholly within the box and having a dial exposed by the window in the cover, a switch mounted in the box, line and load fuse sockets within the box, electrical connections between said switch, meter and fuse sockets, an independently movable cover over the switch and electrical connections aforesaid, a movable guard over the load fuse sockets arranged to be shifted to uncover said load fuse sockets when the inside cover is shifted to uncover the switch and wiring connections, and means for shifting said guard to uncover the fuse sockets when said inside cover is in closed position. 95
35. 9. A meter unit comprising a box, a meter having a wiring chamber housed in said box, a switch in the box, line fuse sockets and load fuse sockets within the box, electrical connections between said switch, meter and fuse sockets, a movable cover over said switch, line fuse sockets and wiring connections arranged to expose the load fuse sockets, an outer cover housing the inner cover and the load fuse sockets, a movable guard over the load fuse sockets, and means for shifting said movable guard to uncover the load fuse sockets when the outer cover is open. 100
40. 10. A meter unit comprising a box, a meter having a wiring chamber housed in said box, a switch in the box, line fuse sockets and load fuse sockets within the box, electrical connections between said switch, meter and fuse sockets, a movable cover over said switch and line fuse sockets and arranged to expose the load fuse sockets, an outer cover housing the inner cover and the load fuse sockets, a movable guard over the load fuse sockets, and means for shifting the same to uncover the load fuse sockets. 105
45. 11. A meter unit comprising a box, a meter having a wiring chamber housed in said box, a switch in the box, line fuse sockets and load fuse sockets within the box, electrical connections between said switch, meter and fuse sockets, a movable cover over said switch, and wiring connections and arranged to expose the load fuse sockets, an outer cover housing the inner cover and the load fuse sockets, a movable guard over the load fuse sockets, and switch operating means arranged to shift the movable guard to cover the load fuse sockets when the switch is in the closed circuit position. 110
50. 12. A meter unit comprising a box, a switch within said box, two sets of fuse sockets within the box, one set of said fuse sockets being elevated above the plane of the other set of fuse sockets, a meter having a wiring chamber housed within the box, wiring connections between said switch, fuse sockets and meter, a movable cover over the switch, wiring connections and the lower set of fuse sockets arranged to expose the elevated set of fuse sockets, and an outside cover over said first cover and the elevated set of fuse sockets. 115
55. 13. A meter unit comprising a box, a switch within said box, two sets of fuse sockets within the box, one set of said fuse sockets being elevated above the plane of the other set of fuse sockets, a meter having a wiring chamber housed within the box, wiring connections between said switch, fuse sockets and meter, a movable cover over the 120
60. 14. A meter unit comprising a box, a switch within said box, two sets of fuse sockets within the box, one set of said fuse sockets being elevated above the plane of the other set of fuse sockets, a meter having a wiring chamber housed within the box, wiring connections between said switch, fuse sockets and meter, a movable cover over the 125
65. 15. A meter unit comprising a box, a switch within said box, two sets of fuse sockets within the box, one set of said fuse sockets being elevated above the plane of the other set of fuse sockets, a meter having a wiring chamber housed within the box, wiring connections between said switch, fuse sockets and meter, a movable cover over the 130

- switch, wiring connections and the lower set of fuse sockets, said movable cover being arranged to expose the elevated set of fuse sockets, and a movable guard over the elevated set of fuse sockets. 5
14. A meter unit comprising a box, a switch within said box, two sets of fuse sockets within the box, one set of said fuse sockets being elevated above the plane of the other set of fuse sockets, a meter having a wiring chamber housed within the box, wiring connections between said switch, fuse sockets and meter, a movable cover over the switch, the wiring connections and the lower set of fuse sockets and arranged to expose the elevated set of fuse sockets, a movable guard over the elevated set of fuse sockets, and an outer cover over said guard and said inside cover. 10
15. A meter unit comprising a box, a meter mounted in said box, a switch within the box, fuse sockets in the box, electrical connections between said switch, meter and fuse sockets, a cover over the switch and wiring connections and arranged to expose the fuse sockets, a guard for covering the fuse sockets movably supported on said cover, and an outer cover for the box arranged to cover the guard and inner cover and provided with a window for exposing the dial of the meter in the box. 15
16. A meter unit comprising a box, a meter mounted in said box, a cover for the box provided with a window for the meter, an inside cover hinged within the box provided with a fuse opening, a switch mounted in the box beneath said inside cover, and a fuse socket mounted in the box in line with the fuse opening in said inside cover. 20
17. A meter unit comprising a box, a meter mounted in said box, a hinged cover for the box provided with a window for the meter, an inside cover hinged within the box provided with a fuse opening, a switch mounted in the box beneath said inside cover, a fuse socket mounted in the box in line with the fuse opening in said inside cover, and a slide mounted on the underside of the inside cover and operably connected with the switch. 25
18. A meter unit comprising a box, a meter having a wiring chamber housed in said box, fuse sockets in the box, electrical connections between said fuse sockets and the wiring chamber of the meter, a cover inside said box and over said wiring connections, a guard for the fuse sockets slidably mounted on the cover, a lock for securing said guard in predetermined position and an outside cover for the entire unit. 30
19. A meter unit comprising a box, a meter having a wiring chamber housed in said box, fuse sockets in the box, electrical connections between said fuse sockets and the wiring chamber of the meter, a cover over said wiring connections, a guard for the fuse sockets slidably mounted on the cover, an outer cover over the first mentioned cover and a lock for securing said outer cover and the guard in predetermined relation. 35
20. A meter unit comprising a switch box, a meter having a wiring chamber housed in said box, a switch mounted in the box and electrically connected with the wiring chamber of the meter, a slide connected with the switch and arranged to be shifted thereby, and means for locking said slide to secure the switch in predetermined position. 40
21. A meter unit comprising a box, a meter having a wiring chamber housed in said box, a switch and fuse sockets mounted in the box, electrical connections between said switch, meter and fuse sockets, a movable cover having a raised portion covering the switch and a depressed portion covering the electrical connections, and a slide supported beneath the raised portion of said cover and arranged to extend over the depressed portion thereof. 45
22. A meter unit comprising, a box, a meter having a wiring chamber housed in said box, a switch and fuse sockets mounted in the box, electrical connections between said switch, meter and fuse sockets, a movable cover having a raised portion covering the switch, a slide supported beneath said raised portion of the cover and connections for operating said slide in conjunction with the movement of the switch. 50
23. A meter unit comprising a box, a meter having a terminal chamber within said box, a switch and line and load fuses within the box and electrically connected with the meter, a cover over said parts arranged to disclose the dial of the meter, a second cover within the box for covering the switch and electrical connections and arranged to leave the load fuses exposed when the outer cover is open, a movable guard for covering the load fuses when the outer cover is open and means for operating said guard to uncover said load fuses. 55
24. In apparatus of the character described, a fuse base having two sets of fuse sockets and one set of said fuse sockets elevated above the plane of the other set of fuse sockets, a cover extending over the lower set of fuse sockets and arranged to leave the upper set of fuse sockets exposed and a movable guard for the upper set of fuse sockets operable to uncover said upper fuse sockets. 60

CLARENCE D. PLATT.
